US00D622129S

(12) **United States Design Patent**
Spivey et al.

(10) **Patent No.:** US D622,129 S
(45) **Date of Patent:** ** Aug. 24, 2010

(54) **KEY SAFE**

(75) Inventors: **Patrick Spivey**, Atlanta, GA (US);
Kenneth C. Krealfe, Atlanta, GA (US)

(73) Assignee: **Base Brands, LLC**, Atlanta, GA (US)

(**) Term: **14 Years**

(21) Appl. No.: **29/321,990**

(22) Filed: **Jul. 28, 2008**

(51) **LOC (9) Cl.** **08-07**

(52) **U.S. Cl.** **D8/333**

(58) **Field of Classification Search** D8/333,
D8/330, 331, 334, 336, 338, 339, 343, 345;
D99/28; 70/14, 18, 20, 24, 25, 31, 35, 38 R,
70/38 C, 51, 55-58, 63, 91, 141; 224/567;
235/382, 382.5; 340/5.73

See application file for complete search history.
